(57) **CLAIM**

The ornamental designs for thermostat, as shown and described.

DESCRIPTION

FIG. 1 is a perspective view of a first embodiment of a thermostat, showing our new design;

FIG. 2 is a front view of the thermostat shown in FIG. 1; FIG. 3 is a right side view of the thermostat shown in FIG. 1;

FIG. 4 is a left side view of the thermostat shown in FIG. 1; FIG. 5 is a top view of the thermostat shown in FIG. 1; FIG. 6 is a bottom view of the thermostat shown in FIG. 1; FIG. 7 is a perspective view of a second embodiment of a thermostat, showing our new design;

FIG. 8 is a front view of the thermostat shown in FIG. 7; FIG. 9 is a right side view of the thermostat shown in FIG. 7;

FIG. 10 is a left side view of the thermostat shown in FIG. 7;

FIG. 11 is a top view of the thermostat shown in FIG. 7; FIG. 12 is a bottom view of the thermostat shown in FIG. 7; FIG. 13 is a perspective view of a third embodiment of a thermostat, showing our new design;

FIG. 14 is a front view of the thermostat shown in FIG. 13; FIG. 15 is a right side view of the thermostat shown in FIG. 13;

FIG. 16 is a left side view of the thermostat shown in FIG. 13;

FIG. 17 is a top view of the thermostat shown in FIG. 13; FIG. 18 is a bottom view of the thermostat shown in FIG. 13; FIG. 19 is a perspective view of a fourth embodiment of a thermostat, showing our new design;

FIG. 20 is a front view of the thermostat shown in FIG. 19; FIG. 21 is a right side view of the thermostat shown in FIG. 19;

FIG. 22 is a left side view of the thermostat shown in FIG. 19;

FIG. 23 is a top view of the thermostat shown in FIG. 19; FIG. 24 is a bottom view of the thermostat shown in FIG. 19; FIG. 25 is a perspective view of a fifth embodiment of a thermostat, showing our new design;

FIG. 26 is a front view of the thermostat shown in FIG. 25; FIG. 27 is a right side view of the thermostat shown in FIG. 25;

(Continued)

FIG. 28 is a left side view of the thermostat shown in FIG. 25;
 FIG. 29 is a top view of the thermostat shown in FIG. 25;
 FIG. 30 is a bottom view of the thermostat shown in FIG. 25;
 FIG. 31 is a perspective view of a sixth embodiment of a thermostat, showing our new design;
 FIG. 32 is a front view of the thermostat shown in FIG. 31;
 FIG. 33 is a right side view of the thermostat shown in FIG. 31;
 FIG. 34 is a left side view of the thermostat shown in FIG. 31;
 FIG. 35 is a top view of the thermostat shown in FIG. 31;
 FIG. 36 is a bottom view of the thermostat shown in FIG. 31;
 FIG. 37 is a back perspective view of the thermostat shown in FIG. 31;
 FIG. 38 is a perspective view of a seventh embodiment of a thermostat, showing our new design;
 FIG. 39 is a front view of the thermostat shown in FIG. 38;
 FIG. 40 is a right side view of the thermostat shown in FIG. 38;
 FIG. 41 is a left side view of the thermostat shown in FIG. 38;
 FIG. 42 is a top view of the thermostat shown in FIG. 38;
 FIG. 43 is a bottom view of the thermostat shown in FIG. 38; and,
 FIG. 44 is a back perspective view of the thermostat shown in FIG. 38.
 The details shown in broken lines in the illustrated embodiments depict environmental subject matter only in those embodiments and form no part of the design claimed with respect to those embodiments. Back views of the thermostat according to the first through fifth embodiments are not shown and form no part of the designs claimed for the thermostat according to the first through the fifth embodiments.
